UNITED STATES PATENT OFFICE.

CHARLEY H. WILKS, OF ARGENTA, ARKANSAS.

TEMPLET.

1,135,089.

Specification of Letters Patent. Patented Apr. 13, 1915.

Application filed March 29, 1913. Serial No. 757,725.

To all whom it may concern:

Be it known that I, CHARLEY H. WILKS, a citizen of the United States, residing at Argenta, in the county of Pulaski and State of Arkansas, have invented a new and useful 5 Templet, of which the following is a specification.

The device forming the subject matter of this application is a templet, adapted to be 10 employed by mechanics for laying out draft sills, draft timbers and other elements used in the making or repair of railroad cars.

The device herein disclosed aims to provide a templet which may be adjusted 15 readily for taking off the lengths of timbers, for marking the bolt holes therein, for marking the key seats, for mortising and tenoning, and for many like operations, 20 commonly met with in the framing of timbers, notably, as hereinbefore stated, in the manufacture and repair of cars.

With the above and other objects in view 25 which will appear as the description proceeds, the invention resides in the combination and arrangement of parts and in the details of construction hereinafter described and claimed, it being understood that 30 changes in the precise embodiment of invention herein disclosed can be made within the scope of what is claimed without departing from the spirit of the invention.

In the drawing: Figure 1 shows the invention in plan, the templet being divided in 35 order that the structure may be shown on a larger scale; Fig. 2 is an elevation showing the finger which is carried at the end of the main rod; Fig. 3 is a cross section on the line 3—3 Fig. 1; Fig. 4 is a cross section on the line 4—4 Fig. 1; Fig. 5 is a sectional detail through the main rod, the view depicting one of the transverse bars which 40 are assembled with the main rod, together with adjacent parts; Fig. 6 is a transverse section on the line 6—6 of Fig. 5; Fig. 7 is a 45 sectional detail illustrating the interlocking relation between certain of the elements shown in Fig. 5; Fig. 8 is a top plan view illustrating one of hole gages and attendant mechanism; Fig. 9 is a perspective showing 50 the interlocking relation between the finger which supports the hole gage and the means whereby the finger is supported; Fig. 10 is a perspective of a transverse bar which is assembled with the main rod; Fig. 11 is a plan 55

of one of the adjustable arms and attendant parts; Fig. 12 is a plan showing another of the adjustable arms and attendant parts; Fig. 13 is a perspective of an auxiliary structure employed in laying off the key 60 seats; Figs. 14 and 15 are plans of timbers which may be laid off by the templet herein disclosed, Figs. 14 and 15 illustrating a few of the many applications of the invention; Fig. 16 is a plan showing a slightly modified 65 form of the invention; Fig. 17 is an elevation of an auxiliary gage which enters into the construction shown in Fig. 1; and Fig. 18 is a perspective showing a clamp which may be employed for holding the templet in 70 place upon the work.

In carrying out the invention there is provided a frame 1 comprising the main member 2 braced as indicated at 3. The main member 2 co-operates with an auxiliary 75 member 4, Fig. 3, the members 2 and 4 of the frame 1 being provided upon their inner faces with pairs of ribs 5 and 6, as shown at best advantage in Figs. 3 and 4. The members 2 and 4 of the frame 1 are provided 80 along their longitudinal edges with projections 7 and 8. The frame 1 is held in place by means of a set screw 9, upon a main rod 10.

The main rod 10 is graduated and is provided 85 at one end with a rectangularly disposed finger 11, held in place by a set screw 12, the finger 11 as clearly shown in Fig. 2, being wider than the main rod 10, in order that the finger 11 may engage one end face 90 of the stick of timber. That end of the main rod 10 which is remote from the finger 11 is provided with a slidably mounted guide 14 held in place by a clamp screw 15, the guide 14 being provided with a rectangularly 95 disposed graduated finger 16 which may be a strip of flat metal.

Located between the members 2 and 4 of the frame 1 and in slidable contact with the ribs 5 is a rod 17 which is provided at one 100 end with a rectangularly disposed arm 18 terminating in a heel 19 which bears slidably upon the main rod 10. Slidable upon the rod 17 and located between the members 2 and 4 of the frame 1 is a rod 20, provided at 105 one end with a rectangularly disposed arm 21 which is shorter than the arm 18, one edge of the arm 21 being rounded or beveled. In slidable contact with the rod 20 is a rod 22, located between the member 2 and 4 of the 110

frame 1, the rod 22 being provided with a short arm 23, one edge of which is rounded or beveled.

Located between the members 2 and 4 of the frame 1 and in slidable contact with the rod 22 is a rod 24. The rod 24 is provided at one end with a rectangularly disposed arm 25, of such a length that the ends of the arms 25 and 18 lie approximately in a common plane. In slidable contact with the rod 24 and in slidable contact with the projections 8 is a rod 26. That end of the rod 26 which is disposed toward the finger 16 is provided with a rectangularly disposed arm 27, the end of which bears slidably upon one edge of the main rod 10, the arm 27 being provided with an outstanding heel 28 which projects outwardly toward the side of the templet. A rod 30 is located between the members 2 and 4 of the frame 1 and is in slidable contact with the ribs 6, Fig. 4. That end of the rod 30 which is adjacent the finger 16 is provided with a rectangularly disposed arm 31 terminating in a heel 32 which bears against one edge of the main rod 10. At this point it may be stated that all of the rods hereinbefore described and described hereinafter, together with accessory parts carried thereby, may be graduated in any desired manner and according to any system, to facilitate the laying off of the work. In slidable contact with the rod 30 is a rod 33. That end of the rod 33 which is disposed toward the finger 11 is provided with a rectangularly placed arm 34 terminating in a heel 35 disposed in slidable contact with the main rod 10. In slidable contact with the rod 33 and in slidable contact with the projections 7 Fig. 3 is a rod 36. That end of the rod 36 which is disposed toward the finger 11 is provided with a rectangularly disposed arm 37.

Slidably mounted upon the main rod 10 between the frame 1 and the finger 11 is a pair of guides 38. The guides 38 may be adjusted along the rod 10 and are held thereon by set screws 39. One guide 38 incloses a bar 40, disposed transversely of the main rod 10, the bar 40 and the rod 10 being pressed together by the set screw 39, as will be understood best from Fig. 8. An extension 41 Fig. 1 is pivoted as indicated at 42 to one end of the bar 40. Mounted to slide upon the bar 40 between the main rod 10 and the pivoted extension 41 is an angular, offset gage 44 comprising a socket 45 Fig. 5 receiving the bar 40, the gage 44 being held in place by a clamp screw 46. This structure is shown in detail in Fig. 17.

Referring to Fig. 6 it will be seen that the bar 40 is provided with a polygonal, longitudinally extended opening 47, receiving slidably, but against rotation, the shank 48 of a head 49, terminally provided with a boss 50 Fig. 5 which outstands at an angle

to the plane defined by the rods 10, 17, 20, 22, 24 26, etc. An arm 51 is provided, the arm 51 lying at right angles to the plane defined by the several rods above mentioned. The arm 51, adjacent one end (see Fig. 9) 75 is provided with a rib 52, registering in a groove 53 formed in the side face of the head 49, transversely of the same. The arm 51 is connected to the head 49 by means of a pivot pin 54. A compression spring 55 surrounds the pivot pin 54, one end of the spring 55 abutting against the head of the pivot pin 54, the other end of the spring 75 abutting against the member 49. The function of the spring 55 is to maintain the rib 80 52 of the arm 51 yieldably interlocked with the groove 53 in the head 49. Mounted to slide upon the arm 51 is a hole gage 56, Fig. 8 the gage 56 including a socket 57 into which the arm 51 is received. The hole gage 85 56 is held in adjusted positions along the arm 51 by means of a clamp screw 58. The hole gage 56 is provided with an opening 59, adapted to define the bolt opening in the timber. The other guide 38 receives a structure which is a duplicate of what has been described hereinbefore, the said structure including a bar 60, an angular gage 61, a pivoted extension 62, a head 63, an arm 64, and a hole gage 65. 90

Slidable upon the main rod 10 is a guide 66 held in place by a set screw 67, the guide 66 receiving a transverse bar 68 provided with an angular gage 69 and with a pivoted extension 70, the slidable head being 100 indicated at 71. The pivoted arm is indicated at 72 and is provided with a hole gage 73. A bar 74 is disposed transversely of the main rod 10 and is held thereon for adjustment both transversely and longitudinally by means of a guide and clamp screw 75. An arm 76 is pivoted to the rod 74, the arm 76 carrying a hole gage 77. The means whereby the arm 76 is connected with the rod 74 embraces the tongue and groove 110 mechanism 52—53 of Fig. 9, the slidable head 49, however, being dispensed with. Adjustably held upon the main rod 10 by means of a guide and screw 78 is a transverse bar 79 (see Fig. 10), provided at one 115 end with an offset 80, carrying a finger 81 lying approximately parallel to the main rod 10. The finger 81 lies upon the opposite side of the main rod 10 from the arm 76.

The parts last above described lie between 120 the frame 1 and the finger 11. Located between the frame 1 and the finger 16 and extended transversely of the main rod 10 is a bar 82, held in place upon the main rod 10 adjustably by means of a clamp and screw 125 83. An arm 84 is adjustably pivoted to one end of the rod 82 and carries a hole gage 85. The bar 82 is provided with an angular, adjustable gage 86, corresponding in construction and in function to the gage 44 130

hereinbefore described and shown in Fig. 17. A bar 87 extends transversely of the main rod 10 and is held adjustably thereon by a clamp and screw 88. To the bar 87 is 5 pivoted an arm 89 provided with a hole gage 90 and with a slidable adjustable finger 91, as shown in Fig. 11. Mounted upon one end of the bar 87 is an angular gage 92 of the sort hereinbefore described. An arm 93 10 extends transversely of the main rod 10 and is adjustably held thereon by a clamp and a screw 94. The bar 93 carries a gage 95 and is provided with an offset finger 96 which lies along one edge of the rod 26. A 15 bar 97 extends transversely of the main rod 10 and is adjustably held thereon by a guide and screw 99. The bar 97 is provided with a slidable head 100, corresponding to and constructed like the head 49 which is shown 20 in Fig. 9. Pivoted to the head 100 is an arm 101 carrying a hole gage 102. A bar 103 extends transversely of the main rod 10 and is slidably and adjustably held thereto by a guide and screw 104. The bar 103 carries a gage 105 and is equipped with a slidable head 106, corresponding to the head 49, there being an arm 107 pivoted to the head 106, the arm 107 carrying an adjustable and 25 hole gage 108. Slidably mounted upon the 30 arm 107, as shown in Fig. 12, is a finger 109.

The invention further includes an angle member shown in Fig. 13 and denoted by the numeral 110, the angle member 110 comprising an arm 111 and a rectangularly disposed arm 112, provided with a shoulder 114. Slidable upon the arm 112 is a yoke 118, and slidable in the yoke 118, transversely of the arm 112 is a gage 117, held in place by a set screw 119. A gage 115 is 35 slidable along the arm 111 and is held in place by means of a clamp screw 116.

In Fig. 16 a modified form of the invention is shown. Many of the parts hereinbefore described are employed, and these 40 parts are designated by the reference numerals already employed, the suffix "a" being added. In the place of the rod 26, however, a rod 200 is employed, provided at one end with a rectangularly disposed arm 201, 45 provided with a pivoted finger 202. A filling block 203 takes the place of the rod 30 and the rod 10 is replaced by a rod 204 provided with a finger 205. The device shown in Fig. 16 is more compact than the 50 structure shown in Fig. 1. The manner of using the structure shown in Fig. 16 does not differ materially from the structure shown in Fig. 1, saving in so far as the omission of parts may alter the operation.

55 In operation, referring particularly to the structure shown in Fig. 1, the bosses 50 Fig. 8 are engaged with one face of a stick of timber, and the several adjustable rods and other movable parts lie along a rectangularly disposed face of the stick. The parts

may be adjusted so that the desired outline may be marked upon the timbers as will be understood readily hereinafter.

The hole gages, of which the gage 56 Fig. 8 may be taken as typical, are employed for laying off the holes which are to be bored in the timber. Owing to the fact that the hole gages, as clearly shown in Fig. 8, are adjustable along the arms, as shown in connection with the arm 51, the holes may be 70 bored near to one edge of the timber or near to the other edge thereof. Owing to the fact that arms, as 51, are pivotally mounted, and owing to the fact that the interlocking elements 52-53 Fig. 9 are provided, the arms may be turned so as to stand in opposite directions, thereby facilitating the laying out of the holes in right and left hand relation.

In Figs. 14 and 15 there are shown a plurality of car timbers which may be laid off by means of the device forming the subject matter of this invention. These figures illustrate some of the applications of the invention only, and are not intended as a 85 complete catalogue of all of the uses to which the device may be put. In order not to obscure the operation of the device by unnecessary verbiage, the operations have been set down in tabular form, one line of 90 numerals in the following tables representing lines on the timbers and the other line of numerals representing the corresponding parts on the templet. In some instances, parts of the templet other than those designated may be employed for laying down the 95 several lines, it being obvious that in a device of this type, much, so far as the the operation is concerned, may be left to the description of the operator and to the work 100 in hand.

For the purpose of securing the templet to the stick of timber, a pair of clamps, 125 may be employed one suitable form of clamp being shown at 250 in Fig. 18.

Having thus described the invention, what is claimed is:—

1. A templet comprising a pair of parallel 130

rods mounted for relative sliding movement in the direction of their lengths and provided with straight, angularly disposed arms, projecting in a common direction and adapted to define the ends of a notch in a stick of timber; a second pair of parallel rods mounted to slide between the rods of the first specified pair, the rods of the second pair having angularly disposed arms projecting in the same direction as the first specified arms, and located between said arms and shorter than said arms, the inner edges of the arms of the second pair of rods being beveled to define a sloping walled recess in the base of the notch; and means for securing the rods in adjusted positions, to permit changes between the relative positions of the arms.

2. A templet comprising a main rod; a guide mounted to slide along the main rod in the direction of the length of the main rod; a bar mounted to slide in the guide transversely of the length of the main rod and held by the guide in a position at right angles to the main rod; clamping means in the guide for holding the bar in adjusted positions with respect to the guide; an arm projecting from the bar at right angles to the plane defined by the rod and the bar; and a gage adjustable along the arm; the movement of the guide along the rod serving to adjust the position of the gage longitudinally of the stick of timber, the movement of the bar in the guide serving to permit the gage to lie flat upon the stick, the movement of the gage along the arm serving to adjust the position of the gage with respect to the face of the stick; and the arm being pivoted to the bar to permit the gage to lie upon either side of the plane defined by the rod and the bar.

3. A templet comprising a pair of parallel rods mounted for relative sliding movement in the direction of their lengths and provided with angularly disposed arms projecting in a common direction and adapted to define the ends of a notch in a stick of timber; a second pair of rods mounted to slide between the rods of the first specified pair, the rods of the second pair having angularly disposed arms projecting in the same direc-

tion as the first specified arms and located between said arms, the arms of the second pair of rods being adapted to define the end walls of a recess in the base of the notch, each rod being movable independently of the other rods; and a means for holding all of the rods in adjusted positions.

4. A templet comprising a clamping frame; parallel main and auxiliary rods longitudinally adjustable in the clamping frame, the main and auxiliary rods having angularly disposed arms projecting in a common direction; a clamp located between the arms and adjustable along the main rod toward and away from either arm; a bar in the clamp and disposed transversely of the main rod, the bar being adjustable with the clamp longitudinally of the main rod and being adjustable in the clamp transversely of the main rod; a gage projecting from the bar and extended longitudinally of the main rod, the gage being adjustable upon the bar longitudinally of the bar and transversely of the main rod.

5. A templet comprising a main rod; a transverse arm on the main rod; supplemental rods disposed on opposite sides of the main rod; a clamping frame in which the rods are longitudinally adjustable; transverse arms at the ends of the respective supplemental rods, the arms being located on opposite sides of the main rod, one of said supplemental rods being movable to position its arm intermediate the arm of the other supplemental rod and the arm of the main rod; a clamp adjustable longitudinally of the main rod; a bar adjustable with the clamp longitudinally of the main rod and adjustable in the clamp transversely of the main rod; and a gage on the bar and extended longitudinally of the main rod, the gage being adjustable longitudinally of the bar and transversely of the main rod.

In testimony that I claim the foregoing as my own, I have hereto affixed my signature in the presence of two witnesses.
